ATTORNEY.

UNITED STATES PATENT OFFICE.

JAMES HARVEY RUTLEDGE, OF PITTSBURG, KANSAS.

CASE FOR FOLDING RULES.

1,351,132.

Specification of Letters Patent. Patented Aug. 31, 1920.

Application filed May 7, 1920. Serial No. 379,579.

To all whom it may concern:

Be it known that I, JAMES H. RUTLEDGE, a citizen of the United States, residing at Pittsburg, in the county of Crawford and State of Kansas, have invented certain new and useful Improvements in Cases for Folding Rulers; and I do hereby declare the following to be a full, clear, and exact description of the invention, such as will enable others skilled in the art to which it appertains to make and use the same.

This invention relates to new and useful improvements in cases especially adapted for holding rulers and pencils and has for its primary object the provision of a device of the above stated character which may be easily and securely fastened to a person's garment and which will receive and hold a pencil and ruler and prevent the same from becoming lost.

Another object of this invention is the provision of an injecting means within the ruler chamber of the case adapted to automatically move the ruler outwardly of said chamber when freed by a catch so that said ruler may be easily gripped and removed for use.

A further object of this invention is the provision of a case for folding rulers and pencils of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description, and accompanying drawings, in which:—

Figure 1 is a front elevation, illustrating a case for a folding rule constructed in accordance with my invention.

Fig. 2 is a vertical sectional view illustrating the same.

Fig. 3 is a rear elevation, illustrating the means of securing the case to a person's garment.

Fig. 4 is a sectional view taken on the line 4—4 of Fig. 2.

Fig. 5 is a sectional view taken on the line 55 5—5 of Fig. 3.

Fig. 6 is a detail perspective view illustrating a catch.

Referring in detail to the drawing, the numeral 1 indicates as an entirety a case 60 which has one end open to form a ruler receiving chamber 2 while its other end is closed by an end wall 3. The case 1 includes front, rear and side walls and the front and side walls are of an integral construction 65 while the rear wall projects beyond the side walls to form an attaching flange, and said side walls are bent about said attaching flange and secured thereto in any well known manner.

An ejecting plate 4 is located within the chamber 2 and free to slide therein and is secured to coil springs 5 which are in turn secured to the end wall 3 and said ejecting plate 4 is transversely curved to form a seat 75 for receiving the end of an ordinary folding or carpenter's rule 6. When the ejecting plate 4 is in its uppermost position, the rule extends outwardly of the chamber 2 so that the same can be readily gripped for remov- 80 ing the same from said chamber for use.

A catch 7 has formed thereon a barrel 8 to receive a pintle 9 that is journaled in one of the flanges of the rear wall and an ear 10 formed on the case so that the head 11 of 85 said catch may move across the open end of the chamber 2 for engaging the end of the ruler and holding the same fully within the chamber and with the ejecting plate 4 moved downwardly against the tension of 90 the springs 5. The catch 7 is offset as illustrated at 12 adjacent the barrel 8 and has seated therein a coil spring 13 which has one end secured to one of the side walls of the case 1 and is adapted to normally urge the 95 head 11 over the open end of the case. The head 11 is provided with an inclined portion 14 adapted to permit a ruler to be readily inserted within the case and when said ruler contacts with the inclined portion 14 causes 100 the catch to swing on its pivot against the tension of the spring and when the ruler has passed beyond said head the spring 13 forces the catch to rock on its pivot and position the head 11 over the end of the ruler 105 retaining said ruler fully within the chamber 2. A guard plate 15 is formed on the offset portion of the catch 12 and overlies

and conceals the spring 13 and prevents the same from being injured during the use of the device. The catch 7 after forming the offset portion 12 is extended or bent to form 5 a finger grip 16 whereby said catch can be readily swung on its pivot to disengage the head 11 from the ruler and permit the ejecting plate 4 to force said ruler partially out of the chamber.

- 10 A pair of fastening elements 17 have one of their ends secured to the rear wall adjacent the open end of the chamber 2 and their other ends are pointed so that said fastening elements can be conveniently inserted 15 through a garment. A keeper 18 is secured to the rear wall adjacent the end wall 3 and is adapted to receive the free ends of the fastening elements 17 after being passed through the garment whereby 20 said case is firmly secured to the garment of a person.

The keeper 18 consists of a plate 19 that has one edge secured to the front wall of the case by a wall 20 and has its opposite 25 edge secured to said case by a tongue 21 which is adapted to form a stop to prevent the fastening elements 17 from moving in the direction or engagement with each other when held in a closed position by the keeper. The side edges of the plate 19 have formed 30 thereon inwardly directed flanges 23 which are adapted to prevent accidental disengagement of the fastening elements 17 from the keeper during the use of the device.

- 35 A cylindrical housing 24 is soldered or otherwise secured to one side wall of the case 1 and is adapted to form a pencil holder and has secured within the same and adjacent its upper end a curved leaf spring 40 25 adapted to be compressed on the insertion of a pencil in the holder and which will prevent said pencil accidentally slipping or falling out of the holder.

While I have shown and described the 45 preferred embodiment of my invention, it will be understood that minor changes in construction, combination, and arrangement of parts may be made without departing from the spirit and scope of the invention 50 as claimed.

Having thus described my invention what I claim is:—

1. A device of the character set forth comprising a ruler receiving chamber, ruler-ejecting means in said chamber, means locking a ruler in said chamber against the ejecting means, and a pencil holder carried by said chamber. 55

2. A case for rulers comprising a body having a ruler receiving chamber, ejecting 60 means in said chamber, a spring actuated catch carried by said body and retaining a ruler within said chamber, and a pencil holder formed on said body.

3. A case for rulers comprising a body 65 having a ruler receiving chamber, an ejecting plate slidably mounted in said chamber, tension means secured to said plate and to the body, a spring actuated catch carried by the body and retaining the ruler within 70 said chamber, and a pencil holder secured to said body.

4. A case for rulers comprising a body having a ruler receiving chamber, an ejecting plate transversely curved and slidably 75 mounted within said chamber, tension means connected to said plate and to the body, a spring actuated catch pivoted to the body and overlying the end of a ruler to retain the same in the chamber, and a pencil 80 holder secured to the body.

5. A case for a ruler comprising a body having one end open to form a ruler receiving chamber, ejecting means in said chamber, a catch pivoted to the body, a head 85 formed on said catch and overlying the open end of said chamber for engagement with the end of the ruler, an offset portion formed in said catch, a guard formed on the offset portion and closing one side thereof, 90 a spring interposed between the offset portion and the body, a finger grip formed on said offset portion.

In testimony whereof I affix my signature in presence of two witnesses.

JAMES HARVEY RUTLEDGE.
